ABSTRACT

A device arranged adjacent a cam ring at jack level in a circular knitting machine. The device includes a movable cam insertable in a notch in the cam ring to maintain the continuity of the upper surface of the cam ring for action upon lower jack butts. When the cam is moved out of the notch a lever is activated to selectively act on jack butts to force the lower butts of selected jacks off the cam ring.

JACK SELECTION DEVICE FOR CIRCULAR KNITTING MACHINES

BACKGROUND OF THE INVENTION

The present invention relates to a device for the selection of the jacks in circular knitting machines, particularly for the manufacture of stockings directly closed at the toe, i.e. stockings which are discharged from the circular machines already closed at the toe without requiring successive sewing.

It is known that stockings obtained directly with the toe closed on circular knitting machines have the disadvantage of a certain thickening of the fabric at the toe.

The main object of the present invention is that of providing a device which, once applied to circular knitting machines, permits the reduction (for example to one half) of the number of needles operating during the manufacture of the toe, so that it is made without thickening of the fabric.

More precisely the device according to the invention permits the reduction of the needles during the phase of manufacture of the stocking toe, or also during other phases, on circular knitting machines not provided with a sufficient number of selection drums for controlling said reduction of the needles.

As is known, the so-called selection drums during their intermittent rotary movement operate horizontal levers which oscillate about vertical axes, and which co-operate by means of blades with the jacks so that they push them, according to a predetermined order and number, into the grooves of the needle cylinder during the selection phase. In the more complete circular machines various drums are provided so as to obtain any type of manufacture. With these machines it is also possible to reduce the number of needles by suitably arranging said drums. In less complete machines, i.e. with repetition cams (memories) in place of the drums, and hence less costly, it is not possible to provide for the said reduction in the needles.

SUMMARY OF THE INVENTION

An object of the invention is that of providing a device which permits the reduction in the needles even in these latter machines.

Another object of the invention is that the said device permits the reduction in needles working in circular knitting machines of the type having eight feeds and two selection drums, or of the type having four feeds and one selection drum. (In the types having eight feeds and four drums or four feeds and two drums, the drums themselves are sufficient to control the reduction in needles, but obviously these types of machine are very complicated and costly.)

A further object of the invention is that of providing a device which is of simple construction, of reliable operation, of easy application and modest cost.

According to the invention there is provided a device for the selection of the jacks in circular knitting machines, to be arranged close to the needle cylinder at the level of the lower ring surrounding the cylinder and provided with triangular cam portions for the raising of the jacks at the various feeds, said device comprising a member which slides outwards or inwards in the preferably substantially radial direction and terminating with an internal section which, in a first position, completes the upper edge of said ring between two adjacent triangular cam portions, and in a second position leaves a corresponding section of the upper edge of said ring open, a selection lever being mounted to oscillate at said sliding member so as to push at least some jacks into the working position in the corresponding grooves of the needle cylinder, and control means for operating said sliding member and said lever, setting this latter in the working position when said sliding member is moved into said second position and viceversa setting said lever in the rest position when said sliding member is moved into said first position.

BRIEF DESCRIPTION OF THE DRAWINGS

The invention will better appear from the following detailed description of a preferred but not exclusive embodiment of a

device for the selection of the jacks according to the invention, illustrated by way of example in the accompanying drawings in which:

5 FIG. 1 is a perspective view of a portion of a circular knitting machine with eight feeds, partially disassembled and provided with the device according to the invention;

10 FIG. 2 is a perspective view of the device according to the invention, separated for clarity from the needle cylinder;

15 FIG. 3 is a diagrammatical perspective view of the device according to the invention in the working position;

20 FIG. 4 is a perspective view similar to that of the preceding Figure in which the device is in the rest position.

DESCRIPTION OF THE PREFERRED EMBODIMENTS

25 With reference to said figs. the device for the selection of the jacks according to the invention comprises a unit 1 mounted on a plate 2 of a circular knitting machine at the needle cylinder 3, in an intermediate position between the selection drums 4 and 5. In the example shown, the device is applied to a circular knitting machine of the type having eight feeds and two drums. As is known these drums rotate intermittently and are prearranged so as to operate a plurality of horizontal selection levers 6 which are mounted to oscillate about a vertical pivot 7. The internal ends of the levers 6 act on blades 6a arranged close to the surface of the needle cylinder 3 so as to be able to push the jacks by acting on their corresponding butts, into the grooves of the cylinder 3.

30 To the plate 2 a ring 8 is fixed which surrounds the cylinder 3 and comprises triangular cam projections which, in the case of the eight feed machine, are four in number. These projections are commonly called cams. More precisely two control cams 9 and 10 and two memory cams 11 and 12 are provided, arranged alternately. The cams 11 and 12 are called memory

35 cams because they cause the precise repetition of the movements made by the other cams 9 and 10.

40 The upper edge of the cams 9-10-11-12 is gleaned, that is radially inclined with the lower side located outwardly, as is the upper edge of the ring 8 between the cams 10 and 11, indicated by 13, and between the cams 9 and 12, indicated by 14 (FIGS. 3 and 4). Between the cams 9 and 11 a flat section 15

45 is provided at which there is the group of blades 6a of the drum 4. Analogously between the cams 10 and 12 another flat section 16 is provided at which there are the blades 6a of the drum 5.

50 The flat sections 15 and 16 are required in order to permit the movement, between the grooves of the cylinder 3, of the jacks 17 (FIGS. 3 and 4). These jacks comprise a lower butt

55 which defines a sharp angled notch 18 which adheres to the gleaned guiding edge of the ring 8, at the cams 9-10-11-12 and at the sections 13 and 14.

The selection device 1 according to the invention, comprises a sliding member 19 disposed in the substantially radial direction at the cylinder 3 and mounted inside a guide body 20 rigid with the plate 2. The internal end portion 21 of the member 19 is shaped similar to the gleaned edge of the sections 13 and 14 of the ring 8. In particular the section 14 is

60 notched at 22 over a portion corresponding to the end 21, so that this latter can be inserted into the notch 22 so as to complete the upper edge of the ring 8. In other words, when the portion 21 is inserted into the notch 22, that is the sliding member 19 is in its first position, the upper edge of the ring 8

65 is perfectly equal to that of a normal ring. The notch 22 defines a flat section of the edge of the ring 8 which permits the pushing of the jacks 17 into the grooves of the cylinder 3 in a manner similar to that which it is possible to do at the flat sections 15 and 16. The pushing of the jacks 17 can be carried

70 out by means of a horizontal selection lever 23 mounted to oscillate on a vertical pin 24 and provided with an internal projection 25 which is suitably connected for engaging with the butt 26 of the jacks 17. The lever 23 is moved against the needle cylinder 3 when the sliding member 19 is in the back or second position. The drawing back of said sliding member 19

can be obtained by means of a lever 27 pivoted at 28 to the plate 2 and acting on a block 29 fixed to said member 19. Said block 29 is attached to the guide block 20 by means of a spring 30 (FIG. 2) which thrusts the member 19 towards the cylinder 3. The position of maximum advancement of the sliding member 19 is determined by a screw 31 attached to the block 29, and engaging, in its limit position, with the guide block 20. By more or less screwing the screw 31 it is possible to adjust the position of maximum advancement of the sliding member 19 in such a manner that the end 21 can be exactly aligned with the edge of the ring 8.

The selection of the jacks 17 is done by excluding for example one half, by excluding one and then leaving the next, so that said half is not raised by the cams 9-10-11-12. The corresponding needles (not shown) are thus not operated. More precisely, one half of the jacks 17 are disposed with their butts 17a at the level of the lever 23, while the other half of the jacks have not butts in that zone. The arrangement of the jacks is an alternate one (FIGS. 3 and 4).

The levers 23 and 27 are attached to corresponding means of operation (not shown) which, in their turn, are connected to cam means.

From the foregoing description, the operation of the selection device according to the invention should be evident.

In the rest or first position, the sliding member 19 is in the position of maximum advancement (FIG. 4) thrust there by the action of the spring 30. In this situation, the circular machine operates in the usual manner, in which on rotating the needle cylinder 3 (in the direction indicated by the arrow A of FIG. 1), the jacks 17 are raised by the cams 9-10-11-12, as clearly shown in FIG. 4. As is known, in circular knitting machines with eight feeds, the four cams 9-10-11-12 of the ring 8 cause the raising of the needles (by way of the jacks 17) at four feeds, while for the remaining four feeds, the raising of the needles is caused by other cams or locks acting directly on the butts of the needles and disposed alternately with the cams 9-10-11b-12 (the cams or locks acting on the butts of the needles are not shown in the drawings).

During manufacture of the toe, only four feeds remain in operation, namely those relative to the cams 9-10-11-12. In the manufacture with direct closing of the toes (obtained by keeping the stocking on the hooks, manufacturing the fabric of the toe and then reversing it) the number of needles worked is halved, in order to obtain a reduction in the thickness of the fabric in this zone.

The reduction in the number of needles takes place, as stated, by making the group 1 operate. More precisely the lever 27 is moved in the direction of the arrow B shown in FIG. 1 and simultaneously the lever 23 is moved against the needle cylinder 3. In this way the sliding member 19 is drawn backwards so as to release the notch 22, while the projection 25 of the lever 23 approaches the needle cylinder 3 (FIG. 3). On rotating this latter, the butts 17a of one half of the jacks 17 engage with said projection 25, so that the jack 17 carrying said butts 17a are pushed into the respective grooves of the cylinder 3. This is possible in that the operation of the lever 23

takes place at the notch 22 which determines a flat section in the edge of the ring 8. The movement of the jacks 17 provided with butts 17a means that the jacks are no longer raised by the cams of the ring 8, but pass inside as shown in FIG. 3. Consequently the corresponding needles are not raised, and are thus excluded from working (i.e. they do not take the thread coming from the four feeds operating).

After manufacture of the toe of the stockings, the unit 1 is returned to its initial disposition, by releasing the lever 27 so as to make the slideable member 19 return into its position of maximum advancement, and returning the lever 23 into its position distanced from the cylinder 3. The return of the member 19 is obtained without interference with the lower butts of the jacks while a group of jacks is in the inoperative position, that is with the lower butts pushed into the grooves of the needle cylinder by the selection levers 6 of the drum 4, which act on the lower butts between cams 11 and 9, as it is known in these machines. The arrangement shown in FIG. 4 is thus attained in which all the jacks 17 are raised by the cams of the ring 8 (i.e. all the needles of the cylinder 3 are again put into operation). Hence in substance the selection device 1 situated before the rise of the cam 12 can make this cam operate as a memory cam or not, according to necessity. As can be seen, the selection device according to the invention is of simple structure and easy manufacture. Its application presents not difficulty and allows an improved operation of circular knitting machines to be obtained which is similar to that of more complete machines.

I claim:

- 30 1. In a circular knitting machine having a needle cylinder with a plurality of grooves therearound, a plurality of needles longitudinally slideable inside said grooves and a plurality of jacks for the actuation of said needles, said jacks having a lower butt and a lower end movable into and out of said grooves, a device for the selection of said jacks according to a predetermined law having a lower ring surrounding the needle cylinder and provided with triangular projections for the raising of the jacks, said ring defining a guiding edge for said lower butt of said jacks, wherein, according to the improvement, the guiding edge defined by said triangular projections and by at least a portion of said ring arranged between two of said triangular projection is inclined in the radial sense having a lower side located outwardly, the said portion defining a notch along a part thereof, and wherein said device further comprises a sliding member movable substantially radially of the needle cylinder and provided with an inner end externally shaped as the said notch to move from a first position in which the said end engages with the said notch to complete the said portion of said guiding edge into a second position in which the said end leaves the said notch open, and wherein said device further comprises a selection lever mounted oscillatingly near said lower ring and having a projection for pushing at least one of said ends of said jacks into the said grooves of said needle cylinder, control means being provided to operate said selection lever and said sliding member and activate said selection lever when said sliding member is in said second position.
